SERVING HEAD

George E. Phillips, Leetsdale, Pa., assignor to
National Electric Products Corporation, a corporation of Delaware

Application July 20, 1940, Serial No. 346,643

10 Claims.

(Cl. 57—3)

This invention relates to a server head for use in the wrapping of cores, such as the cores of insulated electrical conductors, and is a continuation-in-part of my application Serial No. 211,557, filed June 3, 1938.

It is to be understood that the serving head herein disclosed forms part of a complete apparatus primarily purposed to wrap a close helically wound covering jacket of threads around a conductor core as it travels longitudinally through the wrapping instrumentality. The core which is wrapped may be of any desired simplicity or complexity. That is, it may be a simple, solid or stranded, metallic conductive element; it may be an assembly of conductive elements and filling and spacing structure as in the assembly of a non-metallic sheath cable; or it may be as is more usual a metallic conductive element surrounded by an enclosing sheath of vulcanized or unvulcanized rubber or analogous deformable insulating material. The thread may be any twisted or untwisted filament of cotton, paper, "Rayon", "Nylon", or other suitable filamented material.

The server head in which my invention resides is mounted for rotation about the core as the core travels longitudinally, and the server head carries a plurality of bobbins which mount cops or packages of the thread which is to be wound upon the core. The thread or threads from each package pass from it to an appropriate position on the travelling core, being wound thereon as the server head rotates around the core. It is important that the threads be applied to the core under tension, so that they will lie smoothly thereon in a firm enveloping jacket or covering. It is also important, and this is particularly true if the core includes a sheath of unvulcanized rubber, that the tension upon the threads should not be too great. One reason for exerting a moderate, though adequate, tension on the threads is to avoid breakage of the threads; and the other and more exacting reason is to prevent the threads from cutting into the substance of the core, such as a sheath of unvulcanized rubber, because of excessive tension.

In the organization of my server head, certain of the tensioning elements serve as trips to trip a latch controlling the operation of the head, and those elements are supported by threads passing from the bobbin-carried packages to the core. It is important in the operation of the server head that the requisite light tension be maintained approximately uniform at all times in spite of the decreased weight of the packages

of thread as they are progressively exhausted by application of the threads to the core. It is also important that the tensioning elements which are supported by the threads passing to the core should not fail of their support due to loosening of the thread as it tends more freely to unwind when the packages become lighter, but that such support should fail and permit an element of such sort to trip the latch, arresting rotation of the server head only when the thread which supports it becomes discontinuous by breakage or by exhaustion of the package from which it is taken.

Because of technical considerations and manufacturing economy, it is desirable that the cops, or packages, of thread be wound in multiple so that a plurality of threads are taken simultaneously from each of them, to be laid closely side-by-side on the conductor core in the wrapping operation. It is important that these threads should not only be applied under tension of suitable regulated value, but that they also should be so spread and arranged in movement of each group of threads to the core that the threads are laid accurately, without either gaps or overlapping. In operation of the server head the lines of thread passing from the thread-supporting tensioning members to the core, will form different angles with the longitudinal axis of the core in accordance with the desired angle which the threads are to form with that longitudinal axis when they have been laid. I have provided a director instrumentality organized to have edge contact with groups of threads passing from the thread-supporting tensioning members to the core, so to spread and arrange the threads that they come to appropriate position with relation to each other on the core; and have so organized the mounting of that director instrumentality that its edge contact with the groups of threads may be maintained in different angles formed with the longitudinal axis of the core by the groups of threads passing to the core.

I have provided in my server head an organization of tensioning means capable of keeping the reaches of thread passing from the packages of thread to the core under constant and moderate tensioning during consumption of the packages. I have also so adjusted the organization of tensioning means to each other, that the thread-supported tensioning members which serve also as trips for the server head, act to perform that function only under appropriate circumstances.

In the accompanying drawings

Fig. I is a detailed fragmentary elevation partially in vertical section showing the bobbin and bobbin-mounting of a package of thread, and illustrating application of multiple ends of threads from such package to a conductor core.

Fig. II is a schematic plan view of the structure shown in Fig. I.

Fig. III is a fragmentary detail elevational view on an enlarged scale, showing one of the thread-supported tensioning elements of the server head and the inclined track on which it is supported.

Fig. IV is a cross-sectional view through the track upon which the said thread-supported tensioning element moves, showing the tensioning element in end elevation.

Fig. V is a longitudinal sectional view through the said track and tensioning element taken in the plane of the section line V—V of Fig. III.

Fig. VI is a longitudinal sectional view taken in the plane of Fig. V and showing the same structure as in Fig. V, but illustrating a different position of the tensioning element, and the effect of such different position in maintaining moderate tension on the threads.

Fig. VII is a schematic plan view of the server head assembly.

Fig. VIII is a side elevation of a thread-supported tensioning member and the track upon which it moves, corresponding to the showing of Fig. V, but illustrating a slight modification in the structure of the tensioning member.

Fig. IX is a view corresponding to Fig. VI and taken on the section line IX—IX of Fig. VIII, showing the modified form of tensioning member in end elevation.

Fig. X is a longitudinal sectional view through the modified tensioning member and the track on which it moves, corresponding to Fig. VI in the position of the tensioning member and the condition of the thread which supports it.

In the drawings, reference numeral 1 designates a carrier platform rotatably mounted about a hollow spindle 2 through which a core, such as the conductor core A longitudinally travels. On the carrier 1 are a plurality of bobbins, each of which includes a vertical post 3 threaded in the structure of the carrier. A bobbin-spindle 4 which is free to rotate on the post 3 carries squared hubs 5 which engage the tubular core 6 of a cop, or package, B carried by the bobbin. The bobbin mounting includes a nut 7 rigidly connected with the post 3, and the bearing plate 8 which is fixed to the sleeve 4 to rotate therewith and which rests upon the upper surface of the nut. The nut 7 as a mounting element, in cooperation with the plate 8 and under the weight of the bobbin-carried package, determines the frictional resistance which is opposed to rotation of the bobbin in unwinding thread from the bobbin-carried package. It is important that the friction opposing unwinding rotation of the bobbin should not be great, but it is also important that it should not be reduced to a minimum. The importance of moderate regulated friction in the bobbin mounting will be explained in detail in connection with the functioning of other elements of the server head assembly.

Threads from each of the bobbin-carried packages B extend in reaches C from the packages to the core by way of suitable tensioning and directing members. The tensioning assembly includes inclined tracks 9 in the form of flat bars mounted on the carrier structure 1 between the bobbins, and extended upwardly and inwardly toward the

spindle 2 and travelling core A. Tensioning members 10 are slidable on these tracks and are subject both to the force of gravity and to the centrifugal force caused by rotation of the carrying structure, so that these forces tend to move the members 10 downwardly and outwardly along the tracks 9. The reaches of thread from the bobbins pass through holes 11 in the bars 9, and serve normally to support the tension members 10 on the bars or tracks against the forces tending to move them downwardly and outwardly thereon.

As above noted, each of the tension members has a secondary function in addition to its tensioning function. When any one of the members 10 falls because of breakage in the reach of thread by which it is supported, or by exhaustion of the package from which that thread comes, it is moved outwardly and downwardly to trip a latch interrupting the operating connections of the server head and causing the actuation of a brake to bring the head immediately to a stop. Because of this secondary function of the tension members, it is important that they should not so move on the bars or tracks 9 as to produce an undesired stoppage of the head. It is also important that if operation of the server head should be arrested by breakage in the reach of thread associated with one tension member, or by exhaustion of the package from which the thread in that region is taken, stoppage of the machine should not result in unwinding the thread from all the other packages. Such general unwinding would require unnecessary reorganization of the server head requiring the cutting of slack and rethreading from all the packages.

The moderate friction provided in the mountings for the several bobbins, and the structure of the tension members cooperate in preventing both undesired stoppage of the server head and undesired fall of all the tension members when operation of the head is intentionally arrested.

Referring particularly to Figs. III to VI inclusive of the drawings, the tensioning member 10 is shown as of generally tubular form to embrace the bar 9 which provides its track and has outstanding at one edge a flange 17 which performs the tripping function when the tension member falls. In mounted position of the tension member, there are spaces 13 lying between the sides of the bar 9 and the side walls 14 of the tension member. One of the side walls has in it a hole 15, and the other has a hole 16 of greater size than the hole 15, with its lower edge aligned with lower edge of the hole 15, but with its upper edge standing in the assembly at a higher level than the upper edge of the hole 15.

The reach of thread C is threaded through the holes 15 and 16 of the tension member, and through the hole 11 in the bar or track 9. The tension member is therefore supported by the reach of thread pinched between the upper edges of one, or both, of the holes 15 and 16, and the lower edge of the hole 11 in the bar. In normal operation of the server head, with the thread passing uninterruptedly from its packages to the conductor core, the tension member is supported only by contact with the thread at the upper edge of hole 15. If, however, there is undue slackness of the thread, caused by it unwinding too rapidly from its package, the tension member 10 moves on its track enough to cause the upper edge of hole 16 also to rest upon the thread. This double contact, and the tendency for the tension member to move downwardly and outwardly, resolves the slack of the thread into a double

loop, a loop being formed in the space 13 on each side of the bar or track 9. The pinching effect thus created exerts a braking friction on the thread, maintaining the reach of thread taut by tending to retard passage of the thread to its point of application on the core.

Assuming that operation of the serving head is arrested, either by intent or by exhaustion or breakage of the thread forming the supporting reach for any tension member, moderate frictional resistance of the several bobbin-mountings cooperates with the organization of the several tension members which are still supported to retard unwinding of the thread from the packages. In order that there may be moderate friction, adequate for that purpose, the bobbin mountings do not include any sort of bearing to decrease frictional resistance to their rotation. On the contrary there is a surface-to-surface contact between an element connected to turn with the bobbin spindle, illustratively the bearing plate 8, and a non-rotatable mounting element, illustratively the nut 7. It is a simple matter in assembling the server head to use a nut which presents to the bearing plate a surface of such area as to give the desired frictional resistance, and to replace it with a nut of like material, but having a contact surface of greater or lesser area, if it should appear desirable to develop a greater or lesser frictional resistance in the bobbin mounting. Typically, the contact surfaces of the bearing plate and the nut are both smooth, hardened steel, but may either or both be of a different metal if so desired.

The friction in the bobbin mounting being thus sufficiently great to prevent unwinding rotation of the bobbin under the slight weight of the tension element, the slack in the reach of thread extended from the package to the core does not become so great as to permit the tension member in its downward loop-forming movement substantially to unwind the package. In this action the frictional resistance and slack-absorbing characteristics of the tension member tend to prevent substantial unwinding pull on the bobbin-carried package, while the slight frictional resistance to unwinding rotation in the bobbin mounting resists such slight unwinding pull as there is.

A modified form of tension member is shown in Figs. VIII, IX and X of the drawings. That tension element 10a is generally similar to the tension element 10, and carries a trip-operating flange 17a identical with the flange 17 of the member 10. Instead of the holes 15 and 16, it has, however, slots 15a and 16a cut upwardly unequal distances from the lower edges of the two sides 14a of the member. This is the form of tension member specifically disclosed in my prior application, referred to above. The form of tension member previously described has one important advantage over the modified form of tension member. In winding the packages of thread in multiple, the groups of threads are frequently knotted together at their ends. When a package is exhausted it is more likely that a knot will catch at the lower edge of one of the slots 15a and 16a in one of the spaces 13a than at the edge of one of the circular holes 15 and 16. As the catching of a terminal knot in the tension member holds the tension member against downward and outward movement on its track, and thus prevents stoppage of the server head when a package is exhausted, it is an effect which should be avoided.

It is, of course, possible to use the server head to wind single threads from single-wound spools, and by the term "packages" I intend to include such spools as well as those which are wound in multiple. As shown, however, each reach C of thread passing to the conductor core and wound thereon contains a plurality of individual threads, wound in multiple in making up a package and unwound as a unit from it. In serving the core, 10 it is necessary that they lie side-by-side on the core in close contact with each other and without overlap. To do this I provide thread-spreading and thread-arranging means functionally placed between each tensioning member and the core, 15 appropriately to contact the threads of each reach in their passage. The first element of each such means is a pair of spaced pins 18 and 19, mounted in closely spaced position on each of the bars 9 to project from the side of the bar 20 which is functionally adjacent the core. These pins have smooth rounded surfaces, and each group of threads forming a reach is passed over one and under the other pin of a pair, as shown in Figs. I and II of the drawings.

The most important element of the arranging organization is a director head 20, which has a rounded thread-contacting edge. Groups of threads D, after passing over and under the pins 18 and 19, come in contact with the edge of the director head and by that contact are suitably arranged side-by-side, as they reach their position on the core, since they may shift along the rounded edge in response to the pull caused by rotation of the platform around the spindle 2 through which the core passes. The director head is necessarily perforate centrally, and is mounted by a tubular stem 21 in the upper end of spindle 2. The director head is vertically adjustable in the spindle, vertical adjustment being shown as provided by a cooperative threading of its stem 21 and the socket in which the stem fits. In serving the conductor core, the number of individual threads or "ends" which are applied in a single revolution of the server head platform determines the angle which the turns of the applied wrapping form with the longitudinal axis of the core. That angle with which the threads are wrapped follows rearwardly from the core to the edge of the director head which the threads contact. It is important, therefore, that the director head be vertically adjustable to conform with different angles at which it may be desired to apply the served wrapping.

The organization of elements herein particularly specified, or the functional equivalent of such organization of elements, is of a primary importance in obtaining accurate and efficient operation of a server head by which served wrappings are applied to a core, such as an electrical conductor core, at high production speed. Such organization is, therefore, of relatively great importance in contributing to the economical manufacture of insulated electrical conductors which include a served wrapping, or jacket, in their insulating and protective structure.

65 I claim as my invention:

1. In a server head for wrapping a jacket of threads upon a conductor core as it travels comprising a carrier structure rotatable around the conductor core, a plurality of bobbins carrying packages of thread on the carrier structure, and means for leading threads from the packages to the core; the combination of a bobbin-mounting organized under the weight of the bobbin-carried package to oppose moderate frictional re-

sistance to rotation of the bobbin for unwinding thread from the package, and a tension member in the reach of thread passing from the bobbin-carried package to the core and adapted to maintain approximately uniform tension on the thread by opposing to movement of the thread increased frictional resistance as the friction in the bobbin mounting decreases with decreased weight of the bobbin-carried package as the thread unwinds therefrom.

2. In a server-head for wrapping a jacket of threads upon a conductor core as it travels comprising a carrier structure rotatable around the conductor core, a plurality of bobbins carrying packages of thread on the carrier structure, and means for leading threads from the packages to the core; the combination of a bobbin-mounting organized under the weight of the bobbin-carried package to oppose moderate frictional resistance to rotation of the bobbin for unwinding thread from the package, and a tension member in the reach of thread carried from the bobbin-carried package to the core formed and arranged to resolve slackness of thread moving therethrough into confined loops of a length proportioned to the slackness of the thread and thus to maintain approximately uniform tension on the thread by opposing to movement of the thread increased frictional resistance as the friction in the bobbin mounting decreases with decreased weight of the bobbin carried package as the thread unwinds therefrom.

3. In a server head for wrapping a jacket of threads upon a conductor core as it travels comprising a carrier structure rotatable around the conductor core, a plurality of bobbins carrying packages of thread on the carrier structure, and means for leading threads from the packages to the core; the combination of a bobbin-mounting organized under the weight of the bobbin-carried package to oppose moderate frictional resistance to rotation of the bobbin for unwinding thread from the package, and a tension member supported by the reach of thread passing from the bobbin carried package to the core to exert a tensioning effect thereon; the frictional resistance in the bobbin mounting being adequate to prevent unwinding of the bobbin-mounted package under the weight of said tension member when the server head is stationary.

4. In a server head for wrapping a jacket of threads upon a conductor core as it travels comprising a carrier structure rotatable around the conductor core, a plurality of bobbins carrying packages of thread on the carrier structure, and means for leading threads from the packages to the core; the combination of a bobbin-mounting organized under the weight of the bobbin-carried package to oppose moderate frictional resistance to rotation of the bobbin for unwinding thread from the package, and a tension member supported by the reach of thread passing from the bobbin-carried package to the core and adapted to maintain approximately uniform tension on the thread by opposing to movement of the thread increased frictional resistance as the friction in the bobbin mounting decreases with decreased weight of the bobbin-carried package as the thread unwinds therefrom; the frictional resistance in the bobbin mounting being adequate under all conditions of the bobbin-mounted package to prevent unwinding of thread from the said package under the weight of said tension member when the server head is stationary.

5. In a server head for wrapping a jacket of

threads upon a conductor core as it travels comprising a carrier structure rotatable around the conductor core, a plurality of bobbins carrying packages of thread on the carrier structure, and means for leading threads from the packages to the core; the combination of a bobbin-mounting organized under the weight of the bobbin-carried package to oppose moderate frictional resistance to rotation of the bobbin for unwinding thread from the package, and a tension member in the reach of thread passing from the bobbin-carried package to the core and arranged to resolve slackness of thread passing therethrough into friction-increasing loops of a length proportioned to slackness of the thread and thus to maintain approximately uniform tension on the thread by opposing to movement of the thread increased frictional resistance as the friction in the bobbin mounting decreases with decreased weight of the bobbin-carried package as the thread unwinds therefrom; the frictional resistance in the bobbin mounting being adequate under all conditions of the bobbin-mounted package to prevent unwinding of thread from the said package under the weight of said tension member when the server head is stationary.

6. In a core-wrapping assembly composite of a carrier structure rotatable around a longitudinally travelling core and having thereon a plurality of rotatable bobbins carrying packages of thread; the herein described tensioning assembly organized in the reach of thread extended from each bobbin-carried package to the core and constructed to counteract the slackness of thread caused by decreased weight of the said bobbin-carried package as it is unwound by forming one friction-increasing loop with slight slackness in the thread and an additional friction-increasing loop with greater slackness in the thread.

7. In a core-wrapping assembly composite of a carrier structure rotatable around a longitudinally travelling core and having thereon a plurality of rotatable bobbins carrying packages of thread; thread-tensioning means for each bobbin consisting of an inclined bar perforate for passage of threads from the bobbin-carried package to the core, a winged member slidable on the said bar and having at opposite sides of the bar thread-contacting surfaces arranged at different levels with respect to the perforation of the bar, by contact with one or both of which surfaces the thread passing through the bar supports the said member against forces tending to move it downwardly on the bar and by selective contact with one or both of which surfaces slackness of the thread is resolved into one friction-increasing loop with slight slackness in the thread and an additional friction-increasing loop with greater slackness in the thread.

8. In a core-wrapping assembly composite of a carrier structure rotatable around a longitudinally travelling core and having thereon a plurality of rotatable bobbins carrying packages of thread; the herein described novel thread-feeding organization consisting primarily of mountings for the several package-carrying bobbins of the assembly each including opposed contact surfaces organized to produce with each other moderate frictional resistance adequate to prevent free-running of the bobbin in the absence of an unwinding pull on the bobbin-carried package, and thread tensioning means for each bobbin consisting of an inclined bar perforate for passing of threads from the bobbin-carried package to the core, a winged member slidable on the

said bar and having at opposite sides of the bar thread-contacting surfaces arranged at different levels with respect to the perforation of the bar, by contact with one or both of which surfaces the thread passing through the bar supports the said member against gravity and by contact with both of which surfaces slackness of the thread is resolved into one friction-increasing loop with slight slackness in the thread and an additional friction-increasing loop with greater slackness in the thread.

9. In a server head for wrapping a jacket of threads upon a conductor core as it travels comprising a carrier structure rotatable around the conductor core, a plurality of bobbins carrying packages of thread wound in multiple on the carrier structure, and means for leading threads from the packages to the core; the combination of mountings for the said bobbins organized under the weight of the bobbin-carried packages oppose moderate frictional resistance to rotation of the bobbins for unwinding threads from the packages, tension members in the reaches of thread passing from the bobbin-carried package to the core and adapted to maintain approximately uniform tension on the threads by opposing to movement of the thread increased frictional resistance as the friction in each bobbin decreases with decreased weight of the bobbin-carried package as the thread unwinds therefrom, and a director head adapted for edge contact with the said threads in lines inclined to the longitudinal axis of the core followed by the

threads between the tensioning members and the core, by its interposition to spread and arrange the said threads.

10. In a server head for wrapping a jacket of threads upon a conductor core as it travels comprising a carrier structure rotatable around the conductor core, a plurality of bobbins carrying packages of thread wound in multiple on the carrier structure, and means for leading threads from the packages to the core; the combination of mountings for the said bobbins organized under the weight of the bobbin-carried packages to oppose moderate frictional resistance to rotation of the bobbins for unwinding threads from the packages, tension members in the reaches of thread passing from the bobbin-carried package to the core and adapted to maintain approximately uniform tension on the threads by opposing to movement of the thread increased frictional resistance as the friction in each bobbin decreases with decreased weight of the bobbin-carried package as the thread unwinds therefrom, a director head adapted for edge contact with the said threads in lines inclined to the longitudinal axis of the core followed by the threads, and mounting means for the said director head arranged for adjustment of the director head longitudinally of the core to bring it into edge contact with the threads following lines differently inclined to the longitudinal axis of the core.

GEORGE E. PHILLIPS.
